UNITED STATES PATENT OFFICE.

WILLIAM FREDRICK THORNE AND JAMES RANDOLPH INNES HOPKINS, OF WINNIPEG,
MANITOBA, CANADA.

ATTACHMENT FOR SHOCKING-MACHINES.

999,911.

Specification of Letters Patent. Patented Aug. 8, 1911.

Application filed December 6, 1909. Serial No. 531,741.

To all whom it may concern:

Be it known that we, WILLIAM FREDRICK THORNE and JAMES RANDOLPH INNES HOPKINS, both of the city of Winnipeg, in the 5 Province of Manitoba, Canada, have jointly invented certain new and useful Improvements in Attachments for Shocking-Machines, of which the following is the specification.

10 Our invention relates to shocking machines adapted for use with harvesters or binding machines of the ordinary form, the shocker being adapted to be connected to the binder at the side adjoining the binder 15 deck so that the sheaves discharged from the binder will fall on the shocking machine.

Our invention has for its object to produce a sheaf receiving cradle to receive the 20 sheaves thrown down from the binder deck and automatically deposit them in a shock forming basket, it being understood that the shocking machine is of the form which has a frame carrying a pivotally supported 25 shock forming basket into which the sheaves have to be transferred after leaving the binder deck.

It consists essentially in a swinging arm capable of lateral displacement having a 30 sheaf receiving cradle at the end thereof, said arm being suitably mounted on the shocking machine frame, means for operating or swinging the arm, means for alternately displacing the arm laterally to the 35 right and left, and means for grasping or tightening on the sheaf carried by the cradle when the arm is swung, the parts being arranged and constructed as hereinafter more particularly described.

40 Figure 1 is a plan view of a shocking machine equipped with our invention part of the binding machine being shown in dotted outline. Fig. 2 is an enlarged detailed side 45 elevation of the arm operating and deflecting means. Fig. 3 is an enlarged detailed side elevation of the arm, the cradle, and the standard carrying the arm. Fig. 4 is a vertical sectional view through the arm, the section being taken in the plane denoted by 50 the line X X Fig. 3.

In the drawings like characters of reference indicate corresponding parts in each figure.

1 represents the shocker frame which is

formed from longitudinal members 2' and 55 transverse members 3, said frame being supported rearwardly by caster wheels 4 and forwardly by a carriage wheel 5 mounted at the end of a shaft 6 which is secured to the binder frame 7 at 8.

9 represents the binder master wheel and 10 the main shaft of the binder on which the aforesaid wheel is mounted.

11 represents the binder deck from which the sheaves are delivered to the shocking 65 machine.

12 is a box like platform secured centrally in the shocking machine frame in any convenient manner such frame being positioned so that it will receive the sheaves 70 thrown down from the binder.

13 is a converging basket pivotally supported from the rear end of the longitudinal members 2, 2', the large or butt end of the basket being directed rearwardly so that 75 when it is overturned the sheaves collected therein in the form of a shock will be thrown butts down on the ground. The basket is supplied with a longitudinally directed divider 14 which forms an open center for the shock. The forward or head end of the basket 15 overhangs the rear end of the platform 12.

The parts as already described form no 85 part of our present invention but are herein described so as to bring out more clearly the operation of the device which we claim.

A detailed description of the foregoing parts has not been given for the reason that they have already been fully described in a 90 prior application, filed the 12th day of November, 1909, under Serial No. 527745.

In the shocking machine as described in the former application the sheaves delivered from the binder were thrown down directly 95 on to the platform and an attendant sitting on the platform grasped the sheaves and placed them in the basket to either side of the divider. This is a laborious and expensive manner of operating and the present 100 invention has for its object the substitution of an automatically operated device which will do away with the necessity of an attendant on the machine to place the sheaves in the basket.

Rearwardly to the platform we have secured two standards 16 and 17 which are formed with bearings to receive a cross shaft 105

- 18 which has permanently secured to its inner end a gear wheel 19 and crank wheel 20 and carries at its outer end a disk wheel 21. The standard 17 has a partial gear or 5 quadrant 22 mounted thereon which meshes with the gear wheel 19 such quadrant being supplied with a downwardly extending arm 23 to which is connected a drive link 24 fastened at its free end to a part shortly to be 10 referred to.
- 25 is a shaft having an enlarged or flared end which is coupled directly to the shaft 10 of the binder. The shaft 25 extends over the shock ing machine frame and is provided 15 at its end with a loose disk wheel 26 which carries the driven member 27 of a clutch which is engageable with a slideable driving member 28 feathered on the shaft. The driving member is held into engagement 20 with the driven member by means of a spring 29 and can be retracted therefrom by the action of a link 30, the action of which is controlled by the operator on the binding machine, as will readily be understood. 25 The free end of the link 24 is fastened to the disk wheel 26 by a pin 24'. The disk wheel 21 is provided with parallel flanges 21' 21² which pass diametrically across it, the purpose of which is now described.
- 31 is an arm having its one end squared to pass snugly between the flanges 21' 21² said end being pivotally secured to the flanges by means of a vertically directed pin 32. 35 Spiral springs 33 and 34 are interposed between the end of the arm and the face of the disk wheel to either side of the center of the wheel, such springs being held in a set position in any desired manner such as 40 by grooves formed in the respective parts which receive the ends of the springs. According to this mounting the free end of the arm is capable of a swinging motion in a vertical direction when the shaft is turned 45 and is also free to be displaced laterally swinging on the pin 32. The arm is provided with arched bars 35 which form a cradle to receive the sheaves passing from the deck, it being understood that the deck 50 is extended by a sheeting 11' which will direct the sheaves into the cradle when the cradle is in the horizontal receiving position.
- 36 is a lug passing vertically from the standard 16.
- 55 37 is a spiral spring secured to the upper end of the lug at one end and having its other end firmly fastened to the extending end of the arm 31. The spring is constructed so that when the arm is in either 60 of its horizontal positions there is a tendency for it to pass to the vertical position due to the action of the spring and consequently a natural tendency to remain in the vertical position such being the unextended 65 position of the spring.

38 and 39 are lugs passing upwardly and outwardly from one side of the arm adjoining the central bar 35.

40 is an arched catch bar pivotally secured between the lugs 38 and 39, such bar being 70 constructed so that one end 40' extends upwardly within the cradle so as to be thrown downwardly by the deposited sheaf.

41 and 42 are lugs passing upwardly from the bar and carrying slidably a trip rod 43 75 which is connected through a link 44 with the lug 36.

45 is a spring abutting at one end the lug 42 and having the other end fastened to the trip rod. The trip rod is adapted to pass 80 over the end 40' of the catch bar when such end is passed downwardly by the sheaf.

46 and 47 are brackets secured to the platform at the end which adjoins the basket such brackets carrying a rotatable shaft 48 85 which has one end supplied with a disk wheel 49, said wheel being connected through a link 50 with the crank wheel 20 already referred to.

51 is a vertically directed deflecting bar 90 having the upper end turned backwardly on itself at 51' to present an inclined face to receive and displace the arm 31 as later described. The rod has its lower end carried in any convenient form of cup-bearing located on the platform and has the body portion thereof mounted in a suitable bearing formed in a bracket 52 which extends upwardly from the platform.

53 is a gear wheel on the shaft 48 and 54 100 is a second gear wheel on the lower end of the rod, such latter gear wheels meshing the one with the other.

In connection with the parts which operate the arm 31 and the rod 51 it might be 105 mentioned that the gears are constructed and the links placed so that for each half turn of the shaft 18 the rod 51 is turned one-quarter turn. As shown in the drawings these parts have been connected and constructed 110 so that the link 50 rotates the disk wheel 49 one revolution for each forward and backward swing of the arm 31 it being understood that the disk wheel 49 turns always 115 in the same direction. The shaft 48 consequently rotates always in the same direction and carries with it the gear 53 the motion of which rotates the rod 51. The gears 53 and 54 are proportioned so that for one revolution of the shaft 48 the rod 51 is 120 turned one-half of a revolution.

To better understand the invention we will now describe its operation assuming the parts in the position shown and the clutch members in engagement, the binding machine 125 passing forwardly.

A sheaf passes over the deck 11 and sheeting 11' into the cradle. As the sheaf drops it engages with the upturned end 40' of the catch bar and throws the upper end 40² of 130

the bar over the sheaf to a certain extent. Immediately the bar 31 swings upwardly due to the action of the link 24 and co-incident with this motion the trip rod slides 5 over the end 40' acting under the influence of the spring. The trip rod holds the catch bar consequently in a set position so that it is impossible for the sheaf to escape from the cradle when the arm is swinging to the opposite horizontal position. As the arm swings over the rod 51 is turned and assumes the position shown in dotted outline in Fig. 2, so that the bar is deflected to one side of the divider. The sheaf is released from the 10 cradle just prior to the time it assumes the horizontal position over the basket as the trip rod is pulled backwardly by the action of the link 44 thereby releasing the catch bar. When the arm has resumed its original 15 position the rod 51 has turned one-quarter turn in the same direction as formerly so that when the bar is again swung to the receptacle the end 51' of the rod is in a position which will deflect the bar to the opposite 20 side of the divider to that already referred to. This swinging and shifting of the bar continues as long as the machine is in operation so that the shock is evenly built in the basket, the sheaves being delivered alternately 25 to the opposite sides of the divider. When the basket is filled with sheaves the operator stops the movement of the arm by throwing the clutch the basket being then dumped to deposit the shock on the ground.

30 5. What we claim as our invention is:

1. The combination with a shocking machine frame presenting a suitable platform and carrying a shock forming basket having a divider therein, of a reciprocating swinging arm carried by the platform having a sheaf receiving cradle located at its free end, and means engageable with the arm adapted 40 to deflect it alternately to either side of the divider when depositing a sheaf in the receptacle, as and for the purpose specified.

2. The combination with a shocking machine frame presenting a suitable platform and carrying a shock forming basket having a divider therein, of a reciprocating fore 50 and aft swinging arm carried by the platform said arm being mounted to allow its free end to move laterally such end carrying a sheaf receiving cradle, and deflecting means located on the platform adapted to engage with the arm to cause the successive sheaves to pass to either side of the divider when deposited by the cradle in the basket, as and for the purpose specified.

3. The combination with the deck and 55 master wheel of a binding machine, and a shocking machine connected with the binding machine presenting a suitable platform and carrying a shock forming basket having a divider therein of a suitably mounted shaft 60 located on the platform such shaft having a

gear wheel at one end and a disk wheel at the other, said disk wheel having parallel flanges formed thereon, an arm having one end passed between the flanges and pivotally secured thereto, springs interposed between 70 the face of the disk wheel and the arm to either side of the pivotal point, and a sheaf receiving cradle located at its other end, means operated by the master wheel of the binder adapted to oscillate the shaft and reciprocate the arm, and means carried by the platform and engageable with the arm designed to deflect the arm alternately to either side of the divider, as and for the purpose specified. 80

4. The combination with the deck and master wheel of a binding machine and a shocking machine connected with the binding machine presenting a suitable platform and carrying a shock forming basket having a divider therein, of a cross shaft carried by the platform, said shaft having a gear wheel at one end thereof and a disk wheel at the opposite end, the disk wheel being provided with parallel flanges, drive means operated by the master wheel of the binder for oscillating the shaft, an extending arm having one end received between the flanges and pivotally secured thereto by a pin and the opposite end provided with a sheaf receiving cradle, springs interposed between the face of the disk wheel and the arm to either side of the pivotal point, a vertically extending rotatably mounted rod carried by the platform and operated by the aforesaid 90 drive means having its upper end engageable with the arm when reciprocated and adapted in its rotation to deflect the arm alternately to either side of the divider, as and for the purpose specified. 95

5. The combination with a shocking machine frame presenting a suitable platform and having a shock forming basket with a longitudinally directed divider therein and a reciprocating fore and aft swinging arm mounted on the platform and carrying a sheaf receiving cradle at its outer end, said arm being capable of a constrained lateral movement, of a vertically directed rod mounted in suitable bearings carried by the platform and having its upper end turned backwardly to present an inclined face engageable with the arm, and means for turning the rod to cause the cradle to be alternately directed to the opposite sides of the divider when reciprocated, as and for the purpose specified. 105

6. The combination with a shocking machine frame presenting a suitable platform having a shock forming basket with a longitudinally directed divider therein and a reciprocating fore and aft swinging arm mounted on the platform and carrying a sheaf receiving cradle at its outer end, said arm being capable of a constrained lateral 110 movement, of a vertically directed rod mounted in suitable bearings carried by the platform and having its upper end turned backwardly to present an inclined face engageable with the arm, and means for turning the rod to cause the cradle to be alternately directed to the opposite sides of the divider when reciprocated, as and for the purpose specified. 115

movement, of a vertically directed rod mounted in suitable bearings carried by the platform and having its upper end turned backwardly on itself to present an inclined face engageable with the arm, and means designed to turn the rod one quarter turn for each backward and each forward motion of the arm whereby the cradle is directed alternately to the opposite sides of the 10 vider, as and for the purpose specified.

7. The combination with a shocking machine frame presenting a suitable platform and having a shock forming basket with a longitudinally directed divider therein and 15 a reciprocating fore and aft swinging arm mounted on the platform and carrying a sheaf receiving cradle at its outer end, said arm being capable of a constrained lateral movement, of a vertically directed arm 20 mounted in suitable bearings carried by the platform said arm having its upper end turned backwardly on itself to present an inclined face, a gear wheel at the lower end of the rod, a shaft mounted in suitable 25 brackets carried by the frame and carrying a gear wheel meshing with the aforesaid gear wheel, and means for rotating the shaft, said wheels being constructed so as to cause the rod to turn one-quarter turn 30 while the shaft is making one-half the revolution whereby the cradle is deflected to either side of the device successively, as and for the purpose specified.

8. The combination with a shocking machine frame having a suitable platform thereon, of a shaft carried by the platform, said shaft being capable of an oscillatory movement, an arm carried by the shaft and

extending therefrom the free end of the arm carrying a sheaf receiving cradle, an arched 40 catch bar pivotally secured to the arm and adjoining the cradle, said bar having an upturned end engageable with the sheaf received by the cradle whereby the bar is closed over the sheaf when deposited and a 45 releasable trip rod carried by the arm adapted to pass over the upturned end of the bar, as and for the purpose specified.

9. The combination with a shocking machine frame having a suitable platform 50 thereon, of a shaft carried by the platform, said shaft being capable of an oscillatory movement, an arm carried by the shaft and extending therefrom the free end of the arm carrying a sheaf receiving cradle, lugs 55 extending from the arm and adjoining the cradle, an arched bar pivotally secured to the lugs said bar having one of its ends upwardly directed to engage with the sheaf to cause the arm to close over the sheaf when 60 deposited in the cradle, lugs carried by the arm a spring pressed trip rod slidably mounted in said lugs said trip rod being adapted to pass over the upturned end of the bar, a lug extending upwardly from one 65 of the standards adjoining the arm and a link connecting the trip rod with the latter lug, as and for the purpose specified.

Signed at Winnipeg, in the Province of Manitoba, Canada, this 2nd day of November 70 1909.

WILLIAM FREDRICK THORNE.
